PROTECTIVE MASK

Filed Jan. 2, 1931

UNITED STATES PATENT OFFICE

HARRY A. FEE, OF ADRIAN, MICHIGAN

PROTECTIVE MASK

Application filed January 2, 1931. Serial No. 506,159.

This invention relates to protective masks.

This invention has utility when incorporated in a mask to be worn while in unhealthful atmospheres.

5 Referring to the drawing:

Fig. 1 is a side elevation, parts being broken away, of a mask embodying the invention herein;

10 Fig. 2 is a view looking into the mask from the face receiving side thereof;

Fig. 3 is a view on the line III—III, Fig. 2;

15 Fig. 4 is a view on the line IV—IV, Fig. 2;

Fig. 5 is a view on the line V—V, Fig. 1;

15 and

Fig. 6 is a view on the line VI—VI, Fig. 4.

The mask of the invention herein is designed to be worn by persons working in atmospheres surcharged with foreign or obnoxious matter, such as regions in the vicinity of spray painting and the like. The mask is designed to not only protect the eyes and upper face portions, but also to insure to the wearer an ample supply of uncontaminated air while preventing the breathing of unhealthful air, also providing a maximum freedom and comfort to the wearer.

The mask comprises an annular frame 1 designed to encircle a face and is provided with lining 2 of a cushioning means which may be a pneumatic tube, or the like. This construction permits the frame to be comfortably and easily fitted to a wide range of shapes and types of faces. Strap 3 provided with buckle 4 serves as adjustable means for fitting and maintaining the frame on head 5 of a wearer. Attached to the frame 1 is a member 6 forming a visor extending to form a protective shield for the forehead and upper portions of the face. This visor 6 terminates in edge 7 between drop sides 8 which form blinders or side protective shields in the vicinity of the eyes.

45 The visor 6 is provided with fan-shaped duct 9 therethrough to have discharge opening 10 along the edge 7 of this visor, the duct extending to air supply line 11.

The visor is attached to the frame 1, and 50 the duct 9 has needle valve 12 therein for control of the air supply from the line 11 to determine the discharge from the opening 10. The discharge forms a film of air jetted 55 downwardly as a curtain in front of the eyes of the wearer of the mask, tending to

prevent particles of foreign matter passing through the opening provided for vision below the visor. This film or curtain of air is sufficient for normal usages to afford ample protection against particles of material getting into the eyes.

60 The visor 6 has additional duct 13 therethrough from the line 11 and has needle valve 14 therein for controlling air flow to branch line 15 extending downwardly about 65 the frame and through the frame at its lower portion or at a region below the chin receiving portion. This duct 15 is provided with slot 16 having baffle 17 thereabove so that air discharged into the lower portion of the 70 mask from this line 15 is directed outwardly from the wearer.

75 Hinged to the lower portion of the frame 1 is mouth and nose cover 18 contoured to form a shield for the lower face portions while not coming in contact with any part thereof. Spring finger 19 coacts with the line 15 as a snap connection to hold the shield in upward or shielding position. Button 20 facilitates the opening of the shield 80 to allow the wearer to expectorate or attend the nose without removing the mask. The air discharge in the lower portion of the mask from the slot 16 discharges as a film against this shield 18 and is thereby directed 85 upwardly to be breathed by the wearer, the excess and exhaled air being discharged over the upper edge 21 thereof. The edge 21 does not reach the edge 7 of the visor, and there is thus provided clearspace 22 therebetween 90 affording an opening for vision as well as an outlet for excess and exhaled air.

95 The air discharging through the opening between the visor and cover will under some conditions be sufficient alone to protect the wearer from undesirable substances with a resulting economy in the use of air.

In some instances it may be desirable to add a further protection for the eyes and transparency 23 is provided with clips 24 to have slip fit connection with the edge of the visor. This transparency may readily be removed for cleaning without removal of the mask. The transparency may be used in lieu of an air film from the visor or in some 100 instances air may be delivered from the visor when the transparency is attached thereto, the latter especially when unusually fine particles of foreign matter tend to quickly cloud the vision therethrough.

105

110

Under some conditions it may be desirable to provide an expansion chamber 25 in the line 11. This may be of a relatively small volume and be attached to belt 26 of the wearer and the flow thereto controlled by valve 27 in line 28 extending from a suitable source of air supply under pressure. The valve 27 may be adjusted to prevent too great a pressure reaching the line 11. The expansion chamber 25 allows the air to be prewarmed so that when discharged into the mask it will not have a chilling effect on the wearer. The line 11 extending to the belt 26 also prevents a direct pulling of the air supply line on the upper portion of the mask, and also retains the air line 11 out of the way from interference therefrom while working.

There is thus provided a protective mask designed to give maximum comfort to the wearer, to supply a volume of clean air in excess of the breathing capacity of the wearer so that no air will be drawn into the mask from the surrounding atmosphere.

There is also provided a means for creating an air film or curtain across the eyes of the wearer preventing particles of foreign matter getting thereinto, and the hinged nose and mouth shield further add conveniences for the wearer. The removable transparency protects the clear space 22 without obstructing discharge of exhaled air. The air regulators in the branch lines permit a nicety of adjustment to care for a wide range of conditions, while the diffusion of the air in the mask prevents a direct jetting against the face. When used in connection with spray painting, the line 28 may receive its supply from the same source of pressure used by the spraying devices.

The mask may have straps 3 attached in various manners affording comfort to the wearer under different conditions. Also, the mask may be used with one of many of the well-known types of spray painting hoods covering all or any desired portion of the head.

What is claimed and it is desired to secure by United States Letters Patent is:

1. A mask comprising a face encircling band forming a frame having a visor, a lower face portion shield hinged to said frame extending upward to leave a clear space between said shield and visor, and an air supply to said mask having a discharge within the shield.

2. A mask comprising a face encircling band forming a frame having a visor, a lower face portion shield hinged to said frame, an air supply to said frame having a branch extending to discharge at the visor

edge and having a branch to discharge within the shield away from the wearer.

3. A mask comprising a face encircling band forming a frame having a visor, a lower face portion shield hinged to said frame, an air supply to said frame having a branch extending to discharge at the visor edge and having a branch to discharge within the shield outwardly from the wearer against the lower portion of the mouth shield.

4. A mask comprising an annular frame to fit around the face, a visor extending therefrom, a relatively shiftable lower face portion shield hinged to said frame, an air supply extending to the frame having a branch through the visor to be discharged as a film of air from the edge thereof.

5. A mask comprising an annular frame to surround the face, a visor extending therefrom, a relatively shiftable lower face portion shield hinged to said frame, an air supply extending to the frame having a branch through the visor to be discharged as a film of air from the edge thereof, and a branch extending along the frame to discharge into the lower portion of the shield outwardly from the wearer.

6. A mask comprising an annular frame of sheet metal having cushioning means thereabout to surround a face, a visor extending from said frame, a relatively shiftable lower face portion shield hinged to said frame, and a clip carried by said shield cooperating with said frame to hold the shield against the frame in face protecting position.

7. A mask comprising a frame, a visor extending therefrom, a lower face portion shield carried by the frame extending toward the visor and leaving a clear space therebetween, and a transparency having clip fit connection with the free edge of the visor to extend therefrom over said clear space.

8. A mask having a frame, a relatively shiftable lower face portion shield and an air supply to the shield interior comprising a film of air directed away from the wearer onto the lower shield region and upwardly along the shield to be discharged over the top edge thereof.

9. A mask comprising a face encircling band forming a frame having a visor, a lower face portion shield hinged to said frame, an air supply to said frame having a branch extending to discharge at the visor edge and having a branch to discharge within the shield away from the wearer, and an independently controlled air supply for each branch.

In witness whereof I affix my signature.
HARRY A. FEE.
